UNITED STATES PATENT OFFICE.

WILLIAM D. HAVILAND, OF LIMOGES, FRANCE, ASSIGNOR TO THEODORE HAVILAND & CO., OF NEW YORK, N. Y., A FIRM.

DESIGN FOR A PLATE OR SIMILAR ARTICLE.

Application filed May 24, 1922. Serial No. 2,401. Term of patent 14 years.

To all whom it may concern:

Be it known that I, WILLIAM D. HAVILAND, a citizen of the United States of America, and a resident of Limoges, France, have invented a new, original, and ornamental Design for a Plate or Similar Article, of which the following is a specification, reference being had to the accompanying drawing, forming a part thereof and in which is shown a plan view of a plate bearing and embodying my design.

I claim:

The ornamental design for a plate or similar article, as shown.

WILLIAM D. HAVILAND.
